UNITED STATES PATENT OFFICE

2,561,416

SELVAGE FORMING MECHANISM

Philip Worth Robinson, Woodfield Cedars, Ombersley, England, assignor to T. Bond Worth & Sons Limited, Severn Valley Mills, Stourport on Severn, England, a British company

Application July 14, 1947, Serial No. 760,805
In Great Britain February 26, 1946

14 Claims. (Cl. 139—124)

1

This invention relates to a method of and means for forming a selvedge on a fabric woven in looms which employ needles or carriers to carry the weft through the warps instead of inserting the wefts by means of shuttles such looms being referred to in the claims as looms of kind specified. The present invention is particularly applicable to carpet looms or looms for weaving other fabrics which require a firm selvedge which has to be formed by the interlocking of the weft loops with thread, usually passed through the weft loops by small shuttles.

The present invention has for its main object the elimination of the use of shuttles for inserting the thread which binds the weft loops, it having been found in practice that the necessity for filling these shuttles is a major cause of loom stoppages.

Prior proposals for achieving this object have employed a latched needle or a hook especially adapted to act in the manner of a latched needle operating at the side of the fabric at which a selvedge is to be formed, such needle or hook having a knitting action in that a loop of selvedge thread inserted through a weft loop is held on the body of the needle or hook during the next succeeding insertion of selvedge thread and is in such succeeding operation slipped over the end of the needle or hook whereby the newly inserted thread loop is passed through both its associated weft loop and through the prior thread loop. In the case of the unlatched hook a single thread engaged by the hook serves to fill by reason of its cross-sectional dimensions the operative hooked end portion of the hook so that the loop held on the body of the hook may be discharged off the end thereof riding over the engaged single thread which thus acts as a latch in regard to the discharge.

It will be apparent that such an arrangement of hook can work successfully only with a restricted range of thread thicknesses, above which the thread will not be caught up by the hook, and below which the thread will not serve to fill the hooked portion sufficiently to allow the preceding thread loop on the body of the hook to ride over the end.

It is a further object of the present invention to provide a new or improved method of means for achieving the primary object in which the operations of inserting the selvedge thread loop through a weft loop and a previously inserted selvedge thread loop are carried out with greater precision and certainty, and with the possibility of operating at a higher speed thus to reduce

2

the cost of the article, by reason of the definite and positive positioning, holding, and release of said previously inserted selvedge thread loop as compared with the latched needle or equivalent hook method.

Still another object is to avoid the uncertainty in the operation of a latch on a latched needle or the uncertainty of the equivalent mode of operation of the hook as previously described, by the provision of separate and precisely controlled hook retaining and releasing means for the selvedge thread apart from an inserting needle for the latter.

Still another object of the invention is to provide in looms such as carpet looms having a considerable distance between the point where the weft is delivered and the point where it is eventually held in the warps, that is to say having a long beat up, selvedge forming mechanism which includes a member for transferring the looped end of the weft from the first to the second said position so that the selvedge thread can then be inserted through this loop and does not subsequently undergo appreciable displacement with resultant loosening or other undesirable effects on the selvedge as a result of the beating-up action of the loom.

In the accompanying drawings there is shown in a loom of the kind specified one embodiment of apparatus according to the present invention for forming a selvedge and there is also diagrammatically shown the performance of the new or improved method according to the invention.

Referring to the drawings:

Figure 1 is a diagram showing how the weft loops are bound by the thread, this diagram showing the thread inserting needle in its reeded position and the thread hook engaging with a previously inserted loop, the weft inserting needle being omitted for clarity.

Figure 2 is a view similar to Figure 1 showing the parts after the new loop has been inserted by the thread inserting needle through the weft loop and through the thread loop previously inserted. This figure shows the thread hook engaging the new thread loop and the thread inserting needle receding.

Figure 3 is a view in side elevation showing the general arrangement.

Figure 4 is a plan view corresponding with Figure 3.

Figure 5 is a plan view showing the spindle supporting frame and associated parts, the weft inserting needle being shown approaching the guide housing.

Figure 6 is a section on line 6—6 of Figure 5, the weft inserting needle being shown in position in the guide opening.

Figure 7 is a section on line 7—7 of Figure 5.

Figure 8 is a side elevation showing the spindle supporting frame and associated parts.

Figure 9 is a section on line 9—9 of Figure 8.

Figure 10 is a detailed sectional view on line 10—10 of Figure 8.

In the construction illustrated at a suitable position on the loom frame 11 is a support 12 for a spool 13 of thread used for binding the weft loops. The warps are shown at 14, the breast beam at 15 and the take-up device at 16.

Secured to a suitable part 17 of the loom frame is a spindle supporting frame 18, this spindle supporting frame carries three vertical spindles, a primary spindle 19 which can oscillate, a secondary oscillating spindle 20 and a thread hook spindle 21.

Mounted in suitable bearings on the lower part of the loom frame are two parallel horizontal shafts. One of these 22 carries a driving cam 23, the cam groove engaging a roller on a pin 24 carried by an oscillating lever 25 pivoted at 26 to the loom frame. This lever is provided with a second arm 27 connected by a lever 28, the length of which is adjustable, to a crank arm 29 fixed to the spindle 19, the arrangement being such that as the shaft 22 revolves the lever arm 27 is oscillated and through the link 28 and crank arm 29 oscillates the shaft 19. This shaft 19 is provided with a second crank arm 30 connected by a link 31, the length of which is adjustable, to a crank arm 32 fixed on the shaft 20 so that the shaft 20 is oscillated thereby. The shaft 20 has fixed on it a cam 33 which engages a pin or roller 34 on a crank arm 35 fixed to the spindle 21 whereby the spindle 21 is also oscillated. The spindle 21 is provided with a collar 36 having a projecting arm 37 on which is a roller 38 engaged by a face cam 39 on the spindle 20 and between the collar 36 and the lower member of the frame 18 is a spring 40. The spindle 21 is also provided with a collar 41 limiting endwise movement of the spindle. As the cam 39 is oscillated, endwise movement against spring pressure of the spring 40 is imparted to the spindle 21 so that in addition to oscillating the spindle 21 has an up and down movement. At the upper end of the spindle 21 and above the frame 18 is fixed a boss 42 carrying the thread hook 43.

Mounted on the top of the frame 18 is a guide plate 44 having two openings 45, 46.

The shaft 47 which is parallel to the shaft 22 carries a cam 48 in which is a cam groove 49 engaging the pin or roller 50 on a lever arm 51 pivoted at 52 on the loom frame. The lever arm 51 carries a quadrant plate 53 in which are arcuate slots 54 engaged by bolts 55 used adjustably to secure to the quadrant plate 53 the weft hook 56, the upper end of which is adapted to engage the weft loops 57 in succession and to draw them forwardly against the guide plate 44, the operative end of the weft hook engaging in the opening 45 in the guide plate.

Secured to the top of the frame 18 is a guide bracket 58 in which is guided the thread inserting needle 59. This needle has a rectilinear reciprocating movement in the guide holes in the guide bracket.

The upper end of the spindle 13 on the upper side of the frame 18 is provided with a disc 60 oscillating in an opening in the guide bracket and provided with a crank pin 61 which engages

a slot 62 in a cross bar 63 secured to the needle 59 by a screw 64, the arrangement being such that as the shaft 19 oscillates it drives the needle 59 backwards and forwards by the crank pin 61.

Secured to the top of the frame 18 is a guide housing 65. This guide housing is provided with an opening 66 having a tapering mouth for receiving the forward end of the weft inserting needle 67. This guide housing is also provided with an opening 68 for the end portion of the weft hook 56.

The weft inserting needle is provided with the usual opening 69 through which the weft 57 passes and it is further provided with a recess or gap 70 so that the end of the weft hook 56 which is provided with a projection 71 can pass through the lower side of the weft loop and engage the weft.

The guide housing 65 is also provided with a guide hole 72 for the thread inserting needle and on its underside it is provided with a bracket 73 carrying a pin 74 on which is a grooved guide disc 75 for the thread 76 from the spool 13. This thread is taken through the eye 77 of the thread inserting needle 59.

The housing 65 is provided with an open slot 78 in order to enable the weft hook 56 to carry the weft forwardly to the guide plate 44.

The two shafts 22 and 47 are driven at the same speed from the driving shaft of the loom by suitable transmission gear which is not shown.

Referring particularly to Figures 1 and 2 which are diagrammatic only, after each weft loop 57 has been inserted through the shed by the weft inserting needle 67, the thread inserting needle 59 is advanced and carries a loop of the thread 76 through the weft loop and through the loop 79 which has been inserted through the last previously inserted weft loop. This thread loop 79 is held in such position by the thread hook 43 so that it is looped around the line defining the path of the needle 59, that is to say the path of its insertion. As the thread inserting needle 59 moves forwardly to carry the thread through the newly inserted weft loop 57 the said weft loop is drawn forwardly by the weft hook 56. The thread inserting needle 59 after passing through the newly inserted weft loop passes through the thread loop 79 and the thread hook 43 moves up towards the edge of the fabric so that it becomes released from the thread loop of the previously inserted weft loop, the thread hook as it moves towards the edge of the fabric having a relatively slight upward movement produced by the spring 40. The thread hook 43 then moves outwardly again from the side of the fabric and slightly downwardly and passes between the side of the thread inserting needle and the thread 76 which is adjacent thereto and thus holds the newly inserted thread loop shown at 79a in Figure 2 while the needle 59 recedes.

The newly inserted weft loop is held against the guide plate 44 by the weft hook while the operative end of the thread inserting needle 59 passes through the opening 46 in the guide plate 44 and the thread hook 43 engages the thread 76 on the needle while the needle is protruding through the guide plate 44. The thread hook 43 continues to hold the newly inserted thread loop in position so that at the following cycle of operations another loop of thread is inserted through it.

Operation of the fabric take-up device causes the loop 79 to assume in succession the position

shown in Figures 1 and 2 after they have been released by the thread hook 43.

The movements of the thread inserting needle, the weft hook and the thread hook are controlled by the cams 23, 48 and 33 to enable the projection 71 of the weft hook to pass into and through the gap 70 in the side of the weft inserting needle 67 and to engage the weft loop and hold it while the weft inserting needle 67 is withdrawn, after which the weft hook draws the weft loop up to the guide plate 44. The cam groove 49 is shaped to provide for an initial movement of the weft hook 56 to bring its projection 71 into the gap 70 and then to pause before it completes its movement towards the plate 44.

The cam groove in the cam 23 provides for the spindles carried by the frame 18 to remain stationary during about three quarters of the cycle of operations and to provide for a quick oscillation of the spindle during the other quarter of a revolution of the shaft 22.

The end of the thread 76 after passing through the eye of the thread inserting needle is secured to the edge of the fabric at its leading end. It may for instance, be tied to the first weft loop inserted.

What I claim then is:

1. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, and means for moving the thread hook to release it from said previously inserted thread loop and to cause it to engage the thread on the thread-inserting needle and hold it while the thread-inserting needle recedes.

2. In a loom of the kind specified means for interlocking weft loops with thread comprising a weft-inserting element for inserting double shots of weft, said weft-inserting element having a gap in one side near its leading end, a thread-inserting needle, a guide for said thread-inserting needle, adapted to guide said thread inserting needle for movement in a direction approximately parallel to the edge of the fabric, means for reciprocating the thread-inserting needle in said guide so that it may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, and means for moving the thread hook to release it from said previously inserted thread loop and to cause it to engage the thread on the thread-inserting needle

and hold it while the thread-inserting needle recedes.

3. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, the operative end of the weft hook moving approximately parallel to the direction of movement of the thread-inserting needle, both the thread-inserting needle and the operative end of the weft hook moving approximately parallel to the edge of the fabric, a thread hook for engaging and holding a loop of thread which has been previously inserted through the last previously inserted weft loop while the thread-inserting needle passes the new thread loop through said previously inserted thread loop, and means for moving the thread hook to release it from said previously inserted thread loop and to cause it to engage the thread on the thread-inserting needle and hold it while the thread-inserting needle recedes.

4. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, and means for moving the operative end of the thread hook towards and away from the side of the fabric to release it from said previously inserted thread loop and to cause it to engage the thread on the thread-inserting needle and hold it while the thread-inserting needle recedes.

5. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, and means for moving the thread hook towards the edge of the fabric to release it from said previously inserted thread loop and to

cause it to move away from the edge of the fabric and to engage between the thread and the thread-inserting needle so as to hold the thread while the needle recedes.

6. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, and means for moving the operative end of the thread hook in an upwardly-inclined direction towards the edge of the fabric to release it from said previously inserted thread loop and to cause it to move in a downwardly-inclined direction away from the edge of the fabric so as to engage between the thread and the thread-inserting needle so as to hold the thread while the needle recedes.

7. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, means for moving the thread hook to release it from said previously inserted thread loop and to cause it to engage the thread on the thread-inserting needle and hold it while the thread-inserting needle recedes, and a guide plate having an opening, and means for holding each weft loop in turn against one surface thereof while the thread-inserting needle passes through the weft loop and through the opening in the guide plate.

8. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop

while the thread-inserting needle passes the new thread loop through said previously inserted thread loop, means for moving the thread hook to release it from said previously inserted thread loop and to cause it to engage the thread on the thread-inserting needle and hold it while the thread-inserting needle recedes, and a guide plate having a pair of spaced openings, the operative end of the weft hook entering one of said openings to hold the weft loop against one side of said guide plate while the thread-inserting needle passes through the other opening in the guide plate and takes the thread through the loop.

9. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, means for moving the thread hook to release it from said previously inserted thread loop and to cause it to engage the thread on the thread-inserting needle and hold it while the thread-inserting needle recedes, and a guide plate having a pair of spaced openings, the operative end of the weft hook entering one of said openings to hold the weft loop against one side of said guide plate while the thread-inserting needle passes through the other opening in the guide plate and takes the thread through the loop, said thread hook being disposed at the opposite side of said guide plate from that against which the weft loop is held by the weft hook.

10. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being pivotally mounted on the loom frame, means for oscillating said weft hook about the axis of its pivot, said axis being approximately parallel to the weft, a thread hook for engaging and holding a loop of thread which has been previously inserted through the last previously inserted weft loop while the thread-inserting needle passes the new thread loop through said previously inserted thread loop, and means for moving the thread hook to release it from said previously inserted thread loop and to cause it to engage the thread on the thread-inserting needle and hold it while the thread-inserting needle recedes.

11. In a loom of the kind specified means for interlocking weft loops with thread comprising a weft-inserting element for inserting double shots of weft, said weft-inserting element having a gap in one side near its leading end, a thread-insert-

ing needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, means for moving the thread hook to release it from said previously inserted thread loop and to cause it to engage the thread on the thread-inserting needle and hold it while the thread-inserting needle recedes, a spindle-supporting frame, and a guide housing supported on said frame, said guide housing being adapted to guide the thread-inserting needle and the leading end of the weft-inserting needle and receive the weft engaging end of the weft hook as these members pass into said guide housing.

12. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, means for moving the thread hook to release it from said previously inserted thread loop and to cause it to engage the thread on the thread-inserting needle and hold it while the thread-inserting needle recedes, a spindle-supporting frame, and a guide housing supported on said frame said guide housing being adapted to guide the thread-inserting needle and receive the leading end of the weft-inserting needle and the weft engaging end of the weft hook as these members pass into said guide housing, and a guide bracket on said spindle-supporting frame for the thread-inserting needle.

13. In a loom of the kind specified means for interlocking weft loops with thread comprising a weft-inserting element for inserting double shots of weft, said weft-inserting element having a gap in one side near its leading end, a thread-inserting needle, means for guiding and moving the needle transversely to the weft whereby the thread-inserting needle may pass a loop of thread through

the weft loops in succession, a weft hook engaging each weft loop in succession while a loop of thread is inserted therethrough, said weft hook being mounted for movement enabling it to move the weft loop towards the fell of the cloth, a thread hook for engaging and holding a loop of thread which has been previously inserted through the last previously inserted weft loop while the thread-inserting needle passes the new thread loop through said previously inserted thread loop, means for moving the thread hook to release it from said previously inserted thread loop and to cause it to engage the thread on the thread-inserting needle and hold it while the thread-inserting needle recedes, a spindle-supporting frame on the loom, primary and secondary oscillating spindles in said frame, an oscillating thread hook spindle in said spindle-supporting frame, the primary spindle driving the thread-inserting needle and the secondary oscillating spindle having driving means for oscillating the thread hook spindle and having a cam for imparting endwise movement to the thread hook spindle.

14. In the manufacture of a woven fabric in which double shots of weft are inserted by a weft needle in between each shedding operation of the warps, a method of binding in such double shots of weft to form a selvedge edge at the edge of the fabric remote from the edge at which the weft needle first enters the fabric, which method comprises the steps of, withdrawing a loop of weft-thread from the weft needle; moving said weft loop towards the fell of the fabric; holding the weft loop in a position adjacent to the fell of the fabric; inserting a loop of selvedge thread from a bulk thread carrier through said weft loop; holding said inserted selvedge thread loop in such position that it is looped around the line defining the path of its insertion; releasing the weft loop; inserting the next succeeding selvedge thread loop through the next succeeding weft loop which is withdrawn from the weft needle, moved towards and held adjacent to the fell of the fabric in a like manner to the first said weft loop, and through the selvedge thread loop last inserted; releasing the latter and the second said weft loop.

PHILIP WORTH ROBINSON.
